DESIGN FOR A DRAPE HOLDER

Ruth A. Freedman, New York, N. Y.

Application February 5, 1941, Serial No. 98,766

Term of patent 3½ years

To all whom it may concern:

Be it known that I, Ruth A. Freedman, a citizen of the United States of America, residing in the city of New York, county of New York, and State of New York, have invented a new, original, and ornamental Design for a Drape Holder, of which the following is a specification, reference being had to the accompanying drawing, forming part thereof.

Fig. 1 is a plan view of a drape holder showing my new design.

Fig. 2 is an edge view thereof.

Fig. 3 is a rear view of Fig. 1.

Fig. 1 and a portion of Fig. 2 are lined for contrasting colors.

I claim:

The ornamental design for a drape holder, as shown and described.

RUTH A. FREEDMAN.
